UNITED STATES PATENT OFFICE

THOMAS F. CROCKER, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed January 20, 1930. Serial No. 421,980.

The present invention relates in general to telephone systems, but more particularly to automatic telephone systems which include toll or long distance lines in addition to the local subscribers' lines. The object of the invention, broadly stated, is the provision of new and improved circuit arrangements for connecting toll lines with local subscribers' lines and with other toll lines whereby the usual jack and cord circuits at the toll operator's position are eliminated.

In most automatic telephone systems it is common practice to provide a separate group of automatic switches for use by the toll operators in completing toll calls to subscribers' lines. These switches, together with their interconnecting trunk lines, form what is known as a toll service trunking system. In large telephone systems a somewhat similar arrangement known as a toll switching system is provided for interconnecting toll lines at a toll switching center. Special trunking systems are likewise provided for handling outgoing toll calls originating in the area served by a toll board. In all of these systems the usual method of completing connections is by means of cord circuits and the jacks in which the toll lines and trunks terminate. The objectionable features inherent in systems employing cord circuits are overcome in the present invention by the complete elimination of such cords.

The operations involved in setting up connections in systems of the above type, depend more or less on the size of the system. In the larger systems the incoming calls are usually answered by one operator and completed by another operator. The answering or A operator routes a call to the proper completing or B position usually by means of an order wire. The operator at the completing position then extends the call to the wanted subscriber over the usual toll service trunking system. The A operator may also be provided with the equipment for completing a call to a wanted subscriber and also with apparatus for interconnecting toll lines for switching purposes. The completing operator may also be required to handle outgoing toll calls originating in the area served

by the toll office. These calls may be completed directly by the operator while the calling subscriber waits on the line, or may be recorded for completing at a later time.

Efficient routine methods for handling such toll connections have been developed in practice and have become more or less standardized throughout the telephone industry. The operating personnel of most telephone companies have been trained in the use of these methods, hence, radical changes are not desirable. The present invention provides a more efficient and practical system for supplying toll service of the above kind while maintaining the essential features of standardized operation.

The scope of the invention is broadly indicated in the foregoing paragraphs. Various features relating to the operation of the system as a whole will not be specifically mentioned at this time, but will be described in the specification and pointed out in the appended claims.

Fig. 1 shows the A operator's equipment consisting of the position apparatus P and the operator's telephone set T. The position apparatus is common to all toll lines incoming to the position and is provided with a calling device CD and the usual ringing, dialling, splitting and monitoring keys. In this figure is also shown the apparatus OW which is located at the answering position and is associated with an order wire extending to the completing position.

In Fig. 2 is shown the apparatus at a B operator's position. This apparatus is similar in most respects to the apparatus shown in Fig. 1, and includes position equipment P', an operator's telephone set T', and terminal apparatus OW' associated with an order wire extending from the answering position.

Fig. 3 shows the toll lines TL and TL' the former terminating in the relay group TR. This relay group, and other similar relay groups which terminate trunks such as TL', are multiply connected with the position equipment of the A operator's position. Each relay group is provided with a branch extending to a toll selector TS and with a

branch accessible to the B operator's finder switch F.

In Fig. 4 is shown the B operator's finder switch F by means of which the operator can connect with a calling toll line and complete an incoming toll call. A recording and completing trunk circuit RC, also shown in this figure, is accessible to subscribers of the automatic exchange and is provided with a 10 trunk terminating in the selector TS' which has access to outgoing toll lines via connector TC. Trunk RC and other similar trunks are multiply connected with the position equipment of the B position.

15 In Fig. 5 is shown the toll selector TS associated with trunk relay group such as the relay group TR, (Fig. 2). This selector has access to toll line connectors, such as the connector TC, and to toll service trunks, such 20 as the trunk extending to toll transmission selector TTS (Fig. 6). The toll line connector TC is also accessible to the toll selector associated with the recording-completing trunk of the B position.

25 In Fig. 6 is shown, in skeleton form, a toll selector TS', toll transmission selector TTS, a regular exchange toll connector C, line-switch LS, and a local first selector S. The circuit of the selector TS' is identical with 30 that of the toll selector TS (Fig. 5). This selector has access to toll line connectors, such as the connector TC (Fig. 5), and is used by the B operator when completing outgoing toll calls. The remaining switches 35 which are a part of the equipment of the regular automatic exchange are of well known type commonly used for this purpose and since they do not form a part of the invention, it is not considered necessary to 40 show them in detail. The general layout of the automatic exchange is clearly indicated in the drawings.

The subscriber's line from substation A terminates in the lineswitch LS which has access to the local selector S. These selectors have access to the local switches of the exchange and also to the recording-completing trunk, such as the trunk RC, (Fig. 4). The toll service switch train comprises trunks accessible to toll selector TS and terminating in the toll transmission selector TTS which has access to toll connectors, such as the connector C. The connectors have access to the local subscribers' lines in the automatic exchange.

Fig. 7 is a layout diagram showing the manner in which the various sheets of drawings should be arranged in order that the invention may be best understood.

50 The operation of the system may be briefly described as follows: An incoming toll call is indicated by the lighting of the line lamp L of a trunk relay group, such as the relay group TR. The operator connects her telephone set to the line by actuating the asso-

ciated answering key K, and on being informed of the desired connection, will proceed to complete it in one of two ways. If desired, the A or answering operator may complete the call herself, first actuating the dialling key of the position equipment, then dialling up the toll selector TS, transmission selector TTS, and connector C to extend the connection to the local subscriber's line. In case the A operator, for any reason, desires to transfer the call to the B operator for completion, she actuates the key K9 associated with the order wire OW which causes a lamp to light at the B position. The B operator then actuates the key K18 associated with this order wire, and the finder switch F operates to connect with the calling toll line. The A operator then advises the B operator of the destination of the call, the talking circuit being by way of the finder switch F and the trunk relay group. The A operator then restores her answering key and is disconnected from the trunk. To complete the call, the B operator actuates the dialling key of her position equipment, and dials back through the finder switch to operate the toll selector TS, toll transmission selector TTS, and connector C to connect with the wanted line. When the connection is completed the B operator restores her answering key and the finder switch releases and restores to normal. Supervision is given to the A operator by lamps L and L2 associated with the relay group TR. When the conversation is finished and the subscribers hang up this operator releases the apparatus by actuating the release key K1.

The switching of toll calls, that is, the connection of an incoming toll line to an outgoing toll line is handled in exactly the same manner as toll calls to local subscribers. In this case, however, the toll selector TS is operated to select a toll connector switch, such as the connector TC, which is then dialled up to the contacts of the desired toll line.

In the case of toll calls originating in the automatic exchange, the calling subscriber dials the code assigned to the toll recording operator and is connected with a toll recording-completing trunk, such as the trunk RC. The operator is advised of the call by the lighting of the line lamp L5 and answers by actuating the answering key K16 of the trunk circuit. If the call is one that can be quickly completed by the operator, she will then actuate the dialling key of her position equipment and set up a connection to a toll trunk by way of a toll selector such as selector TS' and a toll connector such as the connector TC. The usual supervision is given when the calling party hangs up or when the toll operator at the distant exchange rings off to give the disconnect signal. In the event that the call cannot readily be completed by the operator, the call will be recorded and completed at a

later time in the same manner as an incoming call.

The toll lines shown are arranged for simplex dialling by either of the operators. Composed trunks may also be used without altering the trunk apparatus, and with minor changes the apparatus may be adapted for loop dialling.

- Having briefly described the apparatus and the operation of the invention, a detailed description of the operation will now be given. Assume for example that a toll operator in a distant exchange extends a call over the trunk TL comprising conductors 361 and 362 terminating in relay group TR. The operator at the distant exchange now applies alternating current to the toll line to signal the A operator at the wanted exchange. The signalling current in the left-hand windings of repeating coil R is induced in the right-hand windings thereof which is included in a circuit extending from line conductor 311, normally closed contacts 318, through the winding of alternating current responsive relay 301, condenser 314 to conductor 312. Relay 301 which is of the mechanical locking type, operates in response to the alternating current on the toll line and closes a circuit from ground, normally closed contacts 332, contacts 316, through the lamp L, to battery. The lamp L lights to indicate an incoming call. The circuit for the busy lamp L1 is also closed by relay 301 at contacts 317.

- On noting the lighted condition of the line lamp L, the A operator will actuate the key K associated with the toll line. A circuit is thereby closed from ground, normally closed contacts 341, winding of relay 303, contacts 326, winding of relay 302 to battery, and in parallel therewith through normally closed contacts 334, winding of relay 304 to battery. Relay 302 operates, opens the circuit of relay 301 at contacts 318 and at contacts 319 connects a busy ground to test conductor 310 to mark the toll line busy to connectors such as the connector TC. The unlocking mechanism 315, which is attached to the armature of relay 302, is also actuated and restores the armatures of relay 301 to their normal position, opening contacts 316 and 317. Line lamp L is extinguished, but busy lamp L1 continues to glow, its circuit now being completed by way of contacts 319 and ground. Relay 303 operates and prepares circuits which will be described later. Relay 304 operates, and at contacts 335 locks itself to ground by way of contacts 313 of release-key K1. The impulsing circuit of toll selector TS is prepared at armature 331, a flashing disconnect signal circuit is prepared at contacts 359, and at contacts 337 and 336, respectively, battery through resistance 307 is disconnected from test conductor 310 and ground is substituted therefor.

- The operation of the key K also opens the

direct connection between the toll line and the outgoing trunk associated with the relay group TR, and instead connects the line and trunk by way of the position equipment. A connection may now be traced from conductor 311, contacts 322 of key K, conductor 147, contacts 127 of key K3, contacts 132 and 134, contacts 138 of key K2, conductor 148, contacts 325 of key K to conductor 353, and from conductor 312, contacts 323 of key K, conductor 146, contacts 128 of key K3, contacts 133 and 135, contacts 139 of key K2, conductor 149, contacts 320 of key K, to conductor 349. The operator's telephone set is bridged across the two talking conductors by way of conductors 152 and 153. The circuit of the telephone set is the usual one provided for operator's positions, and includes a receiver RR bridged across one section of the primary winding of a repeating coil R2, and a transmitter connected to the secondary winding of the transformer in series with battery through an impedance 101 and ground.

An additional repeating coil R3 connected up by relay 102 is provided for monitoring purposes. The inward or A operator may now converse with the calling operator over the toll line and determine the connection required.

The operation of the answering key K and relays 303 and 304 of the relay group TR prepared the toll selector LS for operation by completing a circuit extending from ground, normally closed contacts 141 of the dialling key K4 of the position equipment, resistance 109, conductor 150, contacts 327, 344, and 331, conductor 356, thence to the toll selector TS and by way of parallel contacts 521 and 536 through the winding of impulse relay 502 to battery. Relay 502 operates and closes the circuit of relay 503 at contacts 523. Relay 503 operates, completes the circuit of the polarizing winding of relay 506 at contacts 526 and at contacts 527 prepares the circuit of the vertical magnet. Relay 506 does not operate at this time as only its lower winding is energized.

The operator having determined the number of the wanted subscriber, now actuates the dialling key K4 of the position equipment and the previously traced operating circuit of relay 502 is switched over at contacts 142 from ground by way of contacts 141 to ground through the impulse contacts 130 of the calling device CD. When the calling device is turned from its normal position, off-normal contacts 131 complete a circuit for relay 102 by way of contacts 143 of the key K4. Relay 103 operates and at contacts 132 and 133 disconnects the talking conductors associated with the outgoing trunk. As the calling device returns to normal, the circuit of relay 502 is interrupted at the impulse contacts of the calling device and relay 502

responds by deenergizing and reenergizing. Referring now to toll selector TS of Fig. 5, each time relay 502 falls back a circuit is closed from ground, contacts 524, 519, and 527, winding of slow-release relay 504, winding of vertical magnet 508, to battery. The circuit of relay 503 is intermittently opened at contacts 523 during the impulsive but that relay remains energized due to its slow releasing characteristic. The vertical magnet energizes in response to each impulse and steps the shaft and wipers up step-by-step. Relay 504 operates in series with the vertical magnet responsive to the first impulse, and remains operated throughout the series of impulses.

It will be assumed that the digit dialled in this instance is such that the shaft and wipers are raised to the level in which toll 20 service trunks, such as the trunks comprising conductors 545 and 546 terminating in transmission selector TTS, are accessible. On the first vertical step of the wipers, off-normal contacts 511 close and relay 505 operates over a circuit including these contacts and contacts 549 and 526. Relay 505 completes a locking circuit for itself at armature 530, this circuit including interrupter contacts 540, and at contacts 531 prepares a circuit for the rotary magnet. Shortly after the last impulse of the series, relay 504 deenergizes and closes a circuit from ground, contacts 526, 529, and 531 through the winding of rotary magnet 509 to battery. Magnet 509 energizes and steps the wipers in on the first set of contacts in the called level. The circuit of relay 505 is opened at interrupter contacts 540 and relay 505 deenergizes and in turn opens the circuit of the rotary 30 magnet which also deenergizes. In the event that the first trunk of the selected level is busy, test wiper 542 of the selector will encounter a ground applied to multiply connected contacts by another toll selector and this ground, extending by way of contacts 517, interrupter contacts 540, and off-normal contacts 511, will again operate relay 505 which performs the same functions as in the previous instance. The rotary magnet will 40 again energize and step the wipers to the next set of contacts which will be tested in the same manner as the previous set. This testing and stepping operation will be repeated as long as the test wiper encounters 50 grounded contacts. When an idle trunk is encountered, which for the purpose of this description will be assumed to be the trunk comprising conductors 545 and 546, the test wiper will not encounter ground and consequently 60 relay 505 will not operate. Switching relay 501 will now operate over a circuit extending from ground, contacts 526, winding of relay 501, interrupter contacts 540, off-normal contacts 511, through the winding of relay 505 to battery. The resistance of relay 70

501 is relatively high, and relay 505 will not operate over the above traced circuit. It may be noted that relay 501 was prevented from operating when the busy contact was encountered since its winding was shunted by 75 the ground encountered by the test wiper. The test wiper is now disconnected from the upper terminal of relay 501 and connected instead to the lower terminal at contacts 517 and 518, respectively. The impulsive and release circuit of the switch is opened at contacts 519; the impulse conductor from the operator's set is connected up to wiper 543 at contacts 520, but this connection has no utility at present; and the talking conductors 80 355 and 358 are connected up to the right-hand windings of repeating coil R4 at contacts 516 and 522, respectively.

The toll transmission selector TTS, in which the trunks comprising 545 and 546 terminate, may be a selector such as the one disclosed in United States Patent No. 1,664,011, issued to John Wicks, March 27, 1928. The various test contacts associated with the trunks, such as the contacts 547, are multipled in the banks of the various toll selectors and serve the purpose of marking the trunks engaged when a selector, such as the selector TS, has established a connection with the trunks. The operation of the switching relay 501 of selector TS completes a loop circuit for the line relay of the transmission selector extending over conductor 545, wiper 541, contacts 533, upper left-hand winding of repeating coil R4, upper winding of polarized relay 506, contacts 525 and 548, lower left-hand winding of repeating coil R4, contacts 538, wiper 544, and trunk conductor 546. The line relay of the transmission selector operates over the above loop circuit and prepares that switch to receive the dial impulses. Relay 506 does not operate at this time, since the battery flow in its upper winding is in such a direction that the two windings of the relay oppose each other.

The operator now dials the second digit of the wanted number, and relay 502 of toll selector TS responds as in the previous instance. Each time relay 502 drops back in response to an impulse, the loop circuit to the toll transmission selector is opened at contacts 525 and the line relay of the transmission selector responds accordingly. The wipers of the transmission selector are raised to the called level and the selector automatically rotates and selects an idle trunk which may be assumed to be the trunk terminating in connector C. This connector may be similar to the one disclosed in the above referred to Wick's patent. Toll selector TS and transmission selector TTS respond to the last two digits in the usual way, the latter repeating the impulses to connector C are advanced to the contacts of the wanted line, for example, the line comprising conductors 601— 110

603 extending to substation A. If the wanted line is busy, the test wiper of the connector will encounter a grounded contact and the busy tone will be returned to the calling

5 operator in the usual manner. If the wanted line is idle the connector and transmission selector will switch through in the usual way, the latter switch reversing the direction of current flow over the incoming trunk.

10 Relay 506 of toll selector TS will now operate as the two windings of the relay assist each other. A circuit is closed from ground, contacts 532, conductor 357, through the lamp L2 to battery. Lamp L2 lights to inform the

15 operator that the wanted line has been seized.

The operator then actuates the ringing key K2 of the position apparatus, and alternating current is connected to the talking conductors of the trunk by way of contacts 137 and 140. This ringing current is transmitted through the repeating coil R4 of toll selector TS, to the transmission selector TTS to operate an alternating current responsive 25 relay in that switch. The transmission selector, in turn, causes the connector to complete the ringing circuit in the usual manner.

20 The operator may remain on the connection or may disconnect, if desired, by restoring the answering key K, the latter operation again connecting the toll line directly through to the outgoing trunk. Relays 302 and 303 will then deenergize since their circuits are opened at contacts 326, and a holding

25 circuit for impulse relay 502 of toll selector TS will be completed to ground by way of contacts 328. When the called subscriber answers, battery will be disconnected from the trunk conductors incoming to the transmission selector, and relay 506 of the toll selector TS will restore to normal and open the circuit of the lamp L2. Lamp L2 is then extinguished to indicate to the operator that the called subscriber has answered the call.

30 The operator may talk with either subscriber (or operator) to the exclusion of the other by operating the key K and one or the other of cut-off keys K6 or K7. Key K6 closes a circuit for relay 103 which disconnects the calling subscriber (or operator) and key K7 closes a circuit for relay 104 which disconnects the called subscriber (or operator).

35 When the conversation is finished, the called subscriber will hang up and transmission selector TTS will again connect battery to the trunk conductors 545 and 546. Relay 506 will again operate and complete the previously traced circuit of lamp L2 which will light to give disconnect supervision. The operator will ordinarily disregard this signal and wait for the operator in the distant exchange to give the usual disconnect signal. This signal is given by connecting

an alternating current to the toll line at the distant office. The alternating current responsive relay 301, responds as for an incoming call and connects up the lamp L at contacts 316. Relay 304 being operated, however, the circuit of the lamp L will extend to ground through the interrupter I, which will cause the lamp to flash in a characteristic manner. In case a lamp, such as the lamp L2, should remain in lighted condition for a considerable time, the inward operator may cut in on the connection and challenge the toll operator, who may desire another connection. In either case the call may be released by actuating the key K1, thereby opening the circuit of relay 304 at contacts 313.

35 Relay 304 restores and opens the holding circuit of relay 502 of the toll selector at contacts 331 following which the toll selector releases. Relay 502 restores and opens the circuit of relay 503 which also restores, and in turn opens the circuit of relay 501. A circuit for release magnet 510 is then closed from ground, contacts 524, 519, and 528 and off-normal contacts 512. The release magnet energizes to restore the wipers to normal position in the usual way, its circuit being opened at off-normal contacts 512 when the wipers reach the normal position. The loop circuit through the toll transmission selector TTS and connector C is opened at contacts 525 and 548 following the release of relays 502 and 501. These switches release in the usual way and all apparatus involved in the connection is then in condition to receive another call.

40 The A operator may desire to listen in on a call of the character just described, to determine whether or not the transmission is satisfactory and to check other details of the call. For this purpose the monitoring key K8 will be operated, thereby closing a circuit for relay 102 at contacts 120. Relay 102 will energize, disconnect the operator's telephone set from conductors 152 and 153 at contacts 110 and 117, and at contacts 111 and 116 will connect them to the primary winding of the monitoring repeating coil R3. The receiver of the telephone set is disconnected from the usual connection to the primary winding of the repeating coil R2 and bridged across the secondary winding of the repeating coil R3 at contacts 113 and 114. The answering key K of the toll line circuit LR will, of course, be operated and the connection extended through the position apparatus as previously described. When the operator's set is connected up in the above manner, the operator may listen to the call without either subscriber being aware of the fact.

45 In the foregoing description it was assumed that the A operator completed the connection. In actual practice, however, particularly during periods of heavy traffic, the A operator will pass such calls to a B

operator for completion. This is in accordance with the usual operating routine now used in modern telephone systems. The A operator answers the call in exactly the same manner as in the previous case. Relays 302, 303, and 304 of the relay group TR are operated and toll selector TS is prepared for operation as before. After determining the wants of the calling toll operator, instead of dialling up the wanted number as in the previous connection, the A operator momentarily actuates a key, such as the key K9 associated with an order wire, leading to a B position, such as the one shown in Fig. 2. A circuit is thereby closed from ground, contacts 119, conductor 151, contacts 329, through the winding of relay 305 to battery. Relay 305 operates, completes a locking circuit for itself to ground at the release key K1 by way of contacts 338 and 345, closes the rotary marking circuit at contacts 339, and connects ground to the vertical marking circuit at contacts 340, at the same time opening the original energizing circuit of relays 302 and 303 at contacts 341. Relays 302 and 303 restore, the latter relay opening the A operator's dialling circuit at contacts 327 and 330. The above referred to rotary marking circuit now extends from conductor 351, contacts 339, winding of relay 306, winding of relay 302 to battery. The conductor 351 terminates in multiple contacts in the banks of the various finder switches, such as the finder switch F, these contacts being engaged by the test wiper of the finder switch. The operation of the order wire key K9 also closes a circuit from ground, contacts 118, order wire conductor 154, through the winding of relay 209 to battery. This relay and the associated lamp and key are located at the B position, one such order wire and associated apparatus being supplied for each outward position. Relay 209 operates and locks to ground by way of contacts 251 and 241, closes a circuit for the lamp L3 at contacts 242, and a circuit for the lamp L4 at contacts 243. Lamp L3 at the inward operator's position lights to indicate the busy condition of the order wire. Lamp L4 at the outward operator's position lights to apprise the operator of a call awaiting attention.

The B operator on noting the lighted condition of lamp L4 actuates the locking key K18 opening the circuit of relay 209 at contacts 241. Relay 209 restores and opens the circuit of lamps L3 and L4. Lamp L4 is extinguished but lamp L3 continues to glow as its circuit now extends to ground by way of the key contacts 218. The starting circuit of the finder switch F is also completed by the operation of key K18, this circuit extending from ground, contacts 219, starting conductor 254, winding of relay 404, to battery. Relay 404 operates, opens a point in the release magnet circuit at contacts 430 and completes the automatic stepping circuit which now extends from ground, contacts 432, 429, and 426, through the winding of vertical magnet 405 to battery. The vertical magnet energizes over the above circuit, raises the wipers 408—414 one step and completes a circuit for the lower winding of relay 403 at contacts 434. Relay 403 operates, disconnects the vertical magnet from the stepping circuit at contacts 429 and connects it instead to the vertical test wiper 412 by way of contacts 424 and 428 and the upper winding of relay 402. The vertical test wiper engages contacts terminating conductors, such as the conductor 352 to which, as previously explained, ground is connected at the associated relay group by the operation of a relay, such as the relay 305, when the inward operator starts to transfer a call. If the calling toll line is not located in the first level of the finder switch bank, the contacts engaged by wiper 412, following the first vertical step, will not be grounded; hence no circuit will be closed for the upper winding of relay 402. The vertical magnet will deenergize since its circuit has been opened at contact 429, and in turn will open the circuit of relay 403. Relay 403 will deenergize and again connect the magnet to the stepping circuit, whereon the magnet will reoperate and raise the wipers another step. This stepping action will continue until the wiper 412 encounters the contacts associated with the calling toll line, at which time the ground encountered by the wiper will cause the operation of relay 402. The resistance of this relay is relatively high and the vertical magnet will not operate in series therewith although the release of the magnet will be slightly retarded. Relay 402 on operating, completes a locking circuit for itself at contacts 423, disconnects the impulsing conductor 246 from wiper 410 at contacts 421, prepares the rotary testing circuit at contacts 422, opens the vertical testing circuit at contacts 424, disconnects vertical magnet 405 from the stepping circuit at contacts 426, and connects up the rotary magnet 406 at contacts 425. The wipers are thereby stopped opposite the level in which the contacts associated with the calling toll line are accessible. With the first vertical step of the wipers, off-normal contacts 415 close an additional point in the rotary testing set. Following the operation of relay 402 magnet 405 will restore and open the circuit of relay 403 which will also restore, and again complete the automatic stepping circuit which now extends by way of contacts 425 through the winding of rotary magnet 406 to battery. Rotary magnet 406 operates and rotates the wipers one step to the first set of contacts in the level. It will be recalled that in transferring a call, the inward operator causes the line relay group of the calling toll line to mark the line by connecting battery through relays 302 and 306 to

the rotary marking conductor 351, the terminating contact of which is engaged by wiper 411 of the finder switch. If the wanted line is not the first one in the group, wiper 411 will not encounter a potential and the stepping operation will again take place in the same manner as previously described vertical stepping, the wipers being advanced to the next set of contacts in the level. When the line marked as calling is reached, a circuit will be completed from battery, winding of relay 302, winding of relay 306, contacts 339, conductor 351, wiper 411 of the finder switch, upper winding of relay 401, contacts 422, upper winding of relay 403, contacts 431 and 415 to ground. Relay 401 operates, completes a locking circuit for its lower winding at contacts 419, opens the locking circuit of relay 402 at contacts 435, short-circuits its own upper winding at contacts 418, and connects the various talking conductors to the wipers at contacts 416, 417, and 420. Relay 403, which was initially energized by the operation of the rotary magnet, is now held operated over its upper winding in the above circuit and maintains the stepping circuit open at contacts 429. Relay 402 deenergizes and closes points in the operating circuit at contacts 421 and 427. Referring now to the toll line relay group TR, relays 302 and 306 operate over the previously traced rotary testing circuit. The operation of relay 302 has no utility at this time. Relay 306 on operating closes a point in its own circuit at contacts 346 to render it independent of the contacts 339 of relay 305, splits the two branches of the trunk at contacts 342 and 347, transfers the control circuit of selector TS from relay group to the "B" operator's position at contact 343, and at contacts 345 opens the locking circuit of relay 305.

The calling toll line is now connected through both the A and B positions as follows: The upper talking conductor 311 extends by way of contacts 322, conductor 147, contacts 127, 132, 134, and 137, conductor 148, contacts 325, conductor 353, wiper 413 of the finder switch F, contacts 427, conductor 248, contacts 227, 232, 234, and 238, conductor 249, contacts 420, wiper 414, conductor 354, and conductor 355 to toll selector TS. Lower talking conductor 312 extends by way of contacts 323, conductor 146, contacts 128, 133, 135, and 139, conductor 149, contacts 320, conductor 349, wiper 409 of finder switch F, contacts 417, conductor 247, contacts 228, 233, 235, and 239, conductor 250, contacts 416, wiper 408, conductor 348, and conductor 358 to toll selector TS. A control circuit for the toll selector is also completed, this circuit extending from ground at the B position, contacts 222, resistance 208, conductor 246, contacts 421, wiper 410 of the finder switch F, conductor 350, contacts 343 and 331, conductor 356, contacts 521, and 536

in parallel through the winding of relay 502 to battery. Relay 502 is maintained in operated position over this circuit.

The operators' telephone sets at both inward and outward positions are bridged across the talking conductors of the line and trunk as previously described for the inward operator's set. The B operator's set is identical with the previously described A operator's set, and corresponding parts are similarly designated in the drawings. The A operator may now pass the necessary information to the B operator over the talking conductors in the above traced circuit. The toll line is temporarily disconnected by the operation of the cut-off key K6 at the inward position which causes relay 103 to operate and open the talking conductors at contacts 132 and 133. After passing the information, the A operator will disconnect by restoring the key K of the toll line relay group TR to normal, leaving the completion of the call to the B operator.

The B operator then actuates the dialling key K12 at the outward position, and the previously traced circuit of the impulsing relay of the toll selector is transferred from ground by way of contacts 222 to ground by way of contacts 223 and the impulsing contacts 230 of the calling device CD'. When the calling device is turned off-normal, the incoming branch of the trunk is disconnected in the same manner as previously described for the inward position. In this case the relay 204 opens the talking conductors of the trunk at contacts 234 and 235. As the calling device returns to normal, the circuit of relay 502 is interrupted at contacts 230 and relay 502 responds as in the previous instance. The operation of the transmission selector TTS and connector C are exactly the same as in the previously described connection. The B operator, however, receives no supervision since control of the connection is to be maintained by the A operator.

After dialling the last digit of the wanted subscriber's number, the B operator restores the dialling key and also the answering key K18 of the order wire. The circuit of the starting relay 404 of finder switch F is opened, and that relay restores and opens the circuit of relays 401 and 403 of the finder switch and relays 302 and 306 of the relay group TR. These relays all restore to normal. A circuit is closed from ground, off-normal contacts 415, contacts 430 through the winding of release magnet 407 to battery. The release magnet energizes and the wipers of the finder switch are restored to normal position in the usual way, the release circuit being opened at the off-normal contacts when the wipers reach the normal position. In the relay group TR, the restoration of relay 302 is without effect. Relay 306, however, on restoring switches the con-

control circuit of relay 502 of the toll selector from the B position to the relay group by way of contacts 344 and 328. From this point, the supervision and release of the call is in the hands of A operator and is exactly the same as that described in the previous connection.

The circuits are also arranged for toll switching service, as previously stated, that is, they are adapted to operate in a tandem toll switching center for connecting incoming and outgoing toll lines, such as the toll lines TL and TL' which are assumed to extend to different exchanges in the system.

15 The connecting of these two toll lines is carried out by either the A operator or the B operator at the toll switching center as will be described.

The toll operator at the distant exchange 20 signals over the trunk comprising conductors 361 and 362 in the usual way, and the call lamp of the associated relay group TR lights to inform the A operator of the call. The A operator answers the call in the same manner as other incoming calls and may elect to 25 complete the call or pass it to the B operator for completion as in the previously described connection. In either case, the operator completing the call will first dial the digit

30 assigned for toll switching service, whereon the toll selector TS will raise its wipers to the called level and select an idle trunk leading to a toll connector such as the connector TC. Relays 501 to 505, inclusive, of

35 the toll selector function exactly the same as in the previously described connection. When the wipers are raised to the level in which the toll connector trunks are accessible, the shaft springs of the toll selector are operated and a circuit is closed for relay 507 at contacts 513. Relay 507 operates, disconnects the repeating coil R4 from the circuit and connects the talking conductors of

40 the switch straight through to wipers 541 and 544. The shunt around contacts 521 in the circuit of relay 502 is opened at contacts 536 so that the circuit will be opened on the operation of switching relay 501. When an idle trunk is connected with, switching relay

45 501 of the toll selector operates in the usual way to connect the operating and talking conductors through to the wipers of the switch. Assuming that the trunk selected in this case is the one comprising conductors

50 588 to 591, inclusive, terminating in toll connector TC, the control conductor over which relay 502 was operated by way of contacts 521, is now extended to the impulse relay 556 of the connector, by way of contacts 520, 543, and the trunk conductor 590. Relay 556 of the toll connector operates and completes the circuit of relay 555 which also operates. The latter relay prepares the impulsive circuit at contacts 583, and at contacts

trunk conductor 589 to hold the switching relay of the preceding toll selector operated. Returning now to the toll sector, relay 502 restores following the opening of its circuit at contacts 521, and opens the circuit of relay 503 at contacts 523. Relay 503 is slow to release and maintains its armatures actuated a short time after its circuit is opened, and maintains the circuit of relay 501 until the holding ground is returned over the release 75 trunk connector. Relay 503 then restores, closes a point in the release circuit which, however, is now opened at contacts 519 of the switching relay.

The operator now dials the first digit of 80 the number assigned to the wanted toll line, and the circuit of relay 556 is interrupted by the operator's calling device. As relay 556 falls back in response to the first impulse, a circuit is closed from ground, contacts 587, 583, and 560 through the winding of the slow-release series relay 554 and the winding of vertical magnet 557 to battery. The vertical magnet operates to raise the wipers one step. Relay 554 operates and completes an alternate 85 impulsing circuit by way of contacts 580 and off-normal contacts 561 which close on the vertical step of the wipers. The succeeding impulses are transmitted over the alternate circuit, the initial circuit being opened at contacts 560 when the off-normal springs operate on the first vertical step. Shortly after the last impulse of the series, relay 554 restores, opens the alternate impulsing circuit at contacts 580, and at contacts 581 prepares 90 the circuit for the rotary magnet. The operator now dials the final digit and relay 556 responds dropping back to close a circuit from ground, contacts 587, 583, 561, 581, 578 and 570, through the winding of the rotary magnet 558 to battery, and in parallel therewith through the winding of slow-acting relay 552 to battery. The rotary magnet operates to step the wipers around to the contacts of the wanted toll line. Slow relay 552 operates with the first impulse and remains operated throughout the series of impulses, closing an alternate point in the impulsing circuit at contacts 575 to prevent interference by the busy relay as the wipers rotate over 100 busy contact.

If the wanted toll line is busy in another connection, the test conductor of the line will be grounded either at the associated relay group corresponding to the relay group TR, or by a toll connector such as the connector TC. Immediately after the last impulse of the series and before slow-acting relay 552 restores, a circuit is completed from the grounded test conductor, wiper 564, contacts 105 573 and 568, through the winding of busy relay 553 to battery. Relay 553 operates, prepares a locking circuit for itself at contacts 577, opens a point in the impulsing circuit at contacts 578, and at contacts 579 connects the 110

115 120 125 130 135

busy tone to the lower talking conductor of the trunk. This tone informs the operator that the wanted toll line is busy and the operator is expected to release the connection as 5 will be described hereinafter. In case the wanted toll line is idle, the test conductor will be connected to battery at the associated relay group. Busy relay 553 of the connector will not operate at this time. When relay 552 restores shortly after the last impulse of the 10 series, a circuit is closed from this battery on the test conductor, wiper 564, contacts 572, upper winding of relay 551, contacts 576 and 582 to ground. Relay 551 actuates its light 15 tensioned armature and completes a circuit for its lower winding at contacts 569. The lower winding of the relay energizes to fully actuate the armatures and the talking conductors of the switch are connected through 20 to the wipers at contacts 566 and 571, a busying ground is connected to the test wiper at contacts 567, and the previously described impulsive circuit is disconnected from the rotary magnet at contacts 570 and connected 25 to impulsive wiper 589 by way of contacts 588. If the selected toll line terminates in an automatic switch at the distant exchange, the completing operator may further set up a connection by dialing additional digits 30 which are repeated by relay 556 of the connector over the impulsive circuit and wiper to the selected trunk. If the toll line terminates in a manual position, the completing operator will apply ringing current to the 35 line by actuating the ringing key of the position equipment (either key K2 or key K10) to signal the operator at the called exchange. After signalling the wanted exchange, the completing operator will disconnect her telephone set from the toll line by restoring the 40 answering key (K or K18) and the holding circuit of relay 556 of the connector will be transferred to the relay group TR of the calling toll line by way of contacts 331, 344, and 328. Relay 304 of the relay group will 45 remain locked up to ground at the release key K1. The two toll lines are thus connected together by way of the toll selector and toll connector with the alternating current 50 responsive relay 301 of the relay group bridged across the conductors.

When the connection is to be taken down or the A operator is to be recalled, either the calling or called operator will connect ringing current to the toll line to operate relay 551. Relay 301 on operating closes the circuit of lamp L through to the interrupter I and the lamp flashes to indicate this condition to the incoming operator. Before 55 releasing the connection, the operator will actuate the answering key K and challenge the line to determine whether the signal is a recall or a disconnect signal. Relay 302 will operate following the operation of the answering key, and by means of the mechani- 60 cal unlocking device and will restore the armatures of relay 301 to their normal positions. If a connection is to be released, the inward operator actuates the release key K1, thereby opening the circuit of relay 304 which 70 will restore and open the holding circuit of relay 556 at contacts 331. Relay 556 restores and opens the circuit of relay 555 which also restores. Relay 555 removes ground from the release trunk conductor of the incoming 75 trunk, and also opens the holding circuit of relay 551, which relay then restores. A circuit for the release magnet is closed at contacts 584 and the release magnet operates to restore the switch wipers to normal, the circuit being opened at off-normal contacts 562 which open when the wipers reach their normal or home position. In the toll selector, the removal of ground from the release trunk conductor permits the restoration of relay 80 501 which closes a point in the release circuit of the selector at contacts 519. Release magnet 510 then operates in the usual way to restore the switch wipers to their normal position at which time the release circuit is 85 opened at off-normal contacts 512 and the circuit of relay 507 is opened at contacts 513. 90

Originating toll calls are handled by the B operator who functions as a recording-completing operator in this case. By way of example, it will be assumed that the subscriber at substation A desires to call a subscriber at some distant point. When the call is initiated at substation A, lineswitch LS operates in the usual way to extend the calling 95 line to an idle first selector such as the selector S. The calling subscriber then dials the toll operator's code, for instance, the digit "0" and the wipers of selector S are raised to the tenth level. The wipers are then automatically rotated in the well known manner until an idle trunk, such as the trunk comprising conductors 484-486 extending to the toll recording circuit RC is encountered. The calling line loop is extended via conductors 484 and 486 and the right-hand windings of repeating coil R6 to line relay 454. Relay 100 105 454 operates, closes a circuit for relay 455 at contacts 469 and at contacts 468 closes a circuit for lamp L5. Relay 455 operates, connects ground to release trunk conductor 485 at contacts 471 to hold up the switching relay of the selector S, and connects ring-back tone to trunk conductor 486 at contacts 470. The ring-back tone consists of intermittent 110 impulses of ringing current supplied by the generator GEN through condenser C and is controlled by the interrupter I2. The calling subscriber is advised by the tone that the 115 call has been extended to the operator. Lamp L5 lights over the previously traced circuit to inform the operator that a call is awaiting attention. 120

To answer the call, the operator actuates key K16 which bridges the telephone set T' 125

across the left-hand windings of repeating coil R6 via conductors 252 and 253, contacts 232 and 233, contacts 227 and 228, conductors 247 and 248, and contacts 474 and 477. A circuit is also closed from ground, lower winding of relay 451, contacts 478, winding of relay 453, upper winding of relay 452 to battery. These relays energize in series. Relay 451 completes a locking circuit for its upper winding via contacts 458 and contacts 472 of release key K17; prepares the operating circuit of toll selector TS' at contacts 456; prepares the supervisory circuit at contacts 457; and at contacts 459 closes a holding circuit for relay 455. Relay 452 completes a circuit for its lower winding in parallel with relay 455 at contacts 462; opens the circuit of lamp L5 at contacts 460; and disconnects the ring-back tone from the calling line at contacts 461. Relay 453 opens the normal connection of talking conductors 481 and 483 to the left-hand windings of repeating coil R6 at contacts 463 and 466, these conductors now being extended via contacts 475 and 476 of key K16, conductors 249 and 250, contacts 238 and 239 of key K10, contacts 234 and 235, contacts 232 and 233, contacts 227 and 228 of key K11, conductors 247 and 248, and contacts 474 and 477 to the windings of the repeating coil. Relay 453 also extends the control conductor 482 to ground at position equipment P' via contacts 456, 464, and 473, conductor 246, resistance 208, and contacts 222.

The calling subscriber will then give the necessary information to the operator. If the call is one which the operator cannot readily complete, for example a call to a distant city, the operator will record the necessary data and request the calling subscriber to hang up and wait until called back. The data will be passed to an A operator by ticket and this operator will set up a connection to the distant toll office as soon as toll lines are available, as will be described in later paragraphs.

In the event that the call is for a subscriber in some nearby city, the operator may elect to complete the call while the subscriber waits on the line. After requesting the calling subscriber to wait, the operator will actuate key K12 thereby extending control conductor 482 to ground via impulsing contacts 230 of calling device CD'. The operator will then dial the code assigned to a particular toll trunk, the impulses from the calling device over conductor 482 operating toll selector TS' in the same manner as toll selector TS previously described. The selector TS' will connect with an idle toll connector, for example, connector TC which will in turn connect with the wanted toll line such as the line TL. The operator will then ring over the toll line by actuating key K10, or if the toll line terminates in an automatic switch, will dial the re-

quired number to set up the connection at the distant exchange. In either case, when the subscriber at the distant exchange is reached, the operator will restore key K16 and the calling and called subscribers will be connected in talking relation. Relay 451 will remain energized over its upper winding and will maintain the holding circuits for relays 452 and 455. Relay 455 will maintain ground on the release trunk to hold up selector S and lineswitch LS. Relay 453 will restore, switch the control conductor from the operator's set to ground at contacts 465, and will connect talking conductors 481 and 483 directly to the left-hand windings of repeating coil R6. Relay 454 will supply talking current to the calling subscriber and similar current will be supplied to the called subscriber from the distant exchange. There will be no battery connections to the toll line during the conversation.

No supervision is given the originating operator in case the called subscriber hangs up first. When the calling subscriber hangs up, relay 454 will restore and close a circuit from ground via interrupter I', contacts 457 and 467, lamp L5 to battery. Lamp L5 will flash to inform the operator that the calling subscriber has hung up. Before releasing the connection, the operator will actuate key K11 to connect ringing current to the toll line to give a disconnect signal to the operator at the distant exchange, or to release the switches in case the system is arranged for toll line dialing. The operator will then actuate key K17, opening the circuit of relay 451 which restores. Relay 451 in turn opens the circuit of relays 452 and 455 which also restore. Ground is disconnected from control conductor 482 by the opening of contacts 456 and toll selector TS' and connector TC release as previously described. Relay 455 removes ground from release trunk conductor 485 which permits selector S and lineswitch LS to release.

The operator may listen in on connections of the above type by actuating the talking key of the associated trunk, such as the key K16 and the monitoring key K13 of the position apparatus. The actuation of this key closes the circuit of relay 202 which operates to prepare the monitoring circuit which corresponds in all respects to that described for the telephone set T.

The operator may also talk to either party alone in a connection by operating the key K16 and one or the other of cut-off keys K14 or K15. Key K14 closes a circuit for relay 204 which disconnects the called party, while key K15 closes a circuit for relay 203 which disconnects the calling party.

In the case of a recorded toll call such as that previously referred to, the A operator on receiving the ticket containing the necessary data will select an idle toll line to the

wanted office, for example, the toll line TL and will actuate the answering key K of the associated relay group. Relays 302, 303, and 304 will operate as in the previously described 5 connections. Busy lamp L1 will light and calling lamp L will remain dark. The operator will then actuate the dialling key K5 thereby completing a circuit from ground, impulse contacts 130, contacts 123, resistance 10 108, conductor 145, contacts 330 to the mid-point of the left-hand winding of repeating coil R and over the two conductors 361 and 362 of the toll line TL in parallel to a switch at the distant exchange. The operation of 15 the calling device will actuate the switches at the distant exchange in the usual manner.

In case the toll line TL extends to an operator's position, instead of actuating key K5, the operator will actuate key K3 thereby projecting ringing current over the toll line. The operator at the distant exchange will then set up the required connection.

When the wanted subscriber has been connected up, or prior to that time as is more 25 desirable, a connection will be set up over the toll service trunks and switches to the subscriber who originated the call. This part of the connection may be set up by either the A operator or the B operator exactly as 30 described previously for incoming toll calls.

The A operator will receive the usual answering and disconnect supervision. When the calling subscriber hangs up, the A operator will again actuate key K3 to give dis-

35 connect supervision to the distant operator or to release the automatic switches in the distant exchange when such are used. The connection to the calling subscriber is then released as previously described by the actuation 40 of release key K1.

What is claimed is:

1. In a telephone system, a toll line terminating in a manual switchboard, a local trunk terminating in an automatic switch, 45 a link circuit at the switchboard individual to said line and said trunk for connecting the same, a branch of said trunk extending to a second manual switchboard, means for establishing a talking connection between said 50 switchboards via said branch, and means controlled from said second switchboard over said branch for directly operating said switch to extend a connection.

2. In a telephone system, a toll line terminating in a manual switchboard, a local trunk terminating in an automatic switch, a link circuit at the switchboard individual to said line and said trunk for connecting the same, a branch of said trunk extending to 55 a second manual switchboard, and means for directly operating said switch from said first switchboard over said trunk or from said second switchboard over said branch.

3. In a telephone system, a toll line terminating in a manual switchboard, a local

trunk terminating in an automatic switch, a link circuit at the switchboard individual to said line and said trunk for connecting the same, a branch of said trunk extending to a second manual switchboard, means for directly controlling said switch over said trunk from the first switch board, and means for establishing a talking connection between the switchboards via said branch and for rendering said switch directly controllable from the second switchboard over the branch. 70

4. In a telephone system, a toll line terminating in a manual switchboard, a local trunk terminating in an automatic switch, a link circuit at the switchboard individual to 80 said line and said trunk for connecting the same, a branch of said trunk extending to a second manual switchboard, a control circuit for said switch including a conductor of said trunk and a calling device at the first switchboard, and means for disabling said control circuit and for establishing an auxiliary control circuit for the switch including a conductor of said branch and a calling device at the second switchboard. 85

5. In a telephone system, a toll line terminating in an answering position, a local trunk terminating in an automatic switch, a link circuit at said position individual to the line and the trunk for connecting the same, a completing position, and means effective 95 when the line and the trunk are connected for directly controlling said switch from either position to extend a connection.

6. In a telephone system, a toll line incoming to a toll switchboard, a local trunk terminating in an automatic switch, a link circuit at the switchboard individual to said line and said trunk for connecting the same, a branch of said trunk extending to a second switchboard, means at the second switchboard for directly operating said switch over said branch to complete a talking connection from said line to a called subscriber's line, said talking connection excluding the branch of 100 the trunk. 105

7. In a telephone system, a plurality of lines incoming to a toll switchboard, an answering key for each line, a transfer key common to said lines, a second switchboard, operator's telephone sets at each switchboard, a signal at the second switchboard, means responsive to the actuation of one of said answering keys for connecting the associated line to the operator's set at the first switchboard, means responsive to the actuation of the transfer key for marking the connected line and for operating said signal, and a key at the second switchboard for disabling said signal and for connecting the marked line 115 with the operator's set at the second switchboard. 120

8. In a telephone system, a toll line incoming to an operator's position, a key for said line, a second key at said position, a second 130

operator's position, a signal and a key at said second position, means responsive to the operation of both of said keys at the first position for marking said line and for operating said signal, and means responsive to the operation of the key at the second position for disabling said signal and for connecting said line to the second position.

9. In a telephone system, a toll line, an answering key for said line, two operator's telephone sets, a transfer key associated with each set, a finder switch associated with the second set, means responsive to the actuation of said answering key for connecting said line to the first set, and means responsive to the operation of said transfer keys for operating said finder switch to connect said line with the second set.

10. In a telephone system, a toll line, an answering key for said line, two operator's telephone sets, a transfer key associated with each set, means responsive to the actuation of said answering key for connecting said line to the first set, and means responsive to the actuation of both transfer keys for connecting said line with said second set.

11. In a telephone system, a toll line, an answering key for said line, two operator's telephone sets, a transfer key associated with each set, a signal for the second set, means responsive to the operation of said answering key for connecting said line with the first set, means responsive to the momentary operation of the transfer key of the second set for operating said signal, and means responsive to the operation of the transfer key of the second set for disabling said signal and for connecting said line with the second set.

12. In a telephone system, a toll line incoming to an answering position, a trunk having a branch extending to a completing position, a link circuit at the answering position individual to the line and the trunk for connecting the same, a finder switch at said second position, and means controlled jointly from said two positions for operating said finder switch to complete a talking connection between the positions via said branch and said link circuit.

13. In a telephone system, a toll line incoming to an answering position, a trunk having a branch extending to a completing position, a link circuit at the answering position individual to the line and the trunk for connecting them together, a train of automatic switches, means at the completing position for directly operating said switches over said branch to extend a connection from said toll line to a subscriber's line, and means in said link circuit for controlling the release of said connection.

14. In a telephone system, a toll line, two operator's positions, telephone sets at each position, an automatic switch, means including a link circuit for connecting the toll line

with said switch and with the telephone set at the first position, means at the first position for signalling the operator at the second position, a key at the second position for answering the signal, and means responsive to the operation of said key for connecting said two telephone sets in talking relationship and for placing said switch under control of the operator at the second position.

15. In a telephone system, a toll recording trunk incoming to a manual switchboard, means for extending a call to the switchboard via said trunk, means at the switchboard for answering the call, means responsive to the answering of the call for extending a connection from the trunk to an automatic switch, and means at the switchboard for directly operating said switch to extend a connection to an outgoing toll line.

16. In a toll switching system, answering and completing positions, a toll line incoming to the answering position, a toll switch train directly controlled from either position for extending a connection to a subscriber's line, and a link circuit at the answering position individual to the toll line for connecting the same with said switch train.

17. In a telephone system, a toll line terminating in an answering position, a local trunk terminating at said position, a branch of said trunk extending to a completing position, a link circuit at the first position, means including the link circuit for answering calls extended over said line and for connecting said line and said trunk, and means including a switch controlled jointly from said two positions for completing a talking connection between the positions over said branch.

18. In a telephone system, a cordless toll switchboard comprising two positions, toll lines, means at the first position for answering calls extended over said toll lines, means for transferring the calls to the second position for further extension to another toll line or to a subscriber's line, means for disconnecting the second position when the extension is completed, and means at the first position for supervising the calls so extended.

19. In a telephone system, a cordless toll switchboard comprising two positions, toll lines, means at the first position for answering calls extended over said toll lines, means for transferring the calls to the second position for completion of the connections via automatic switches, and means at the first position for supervising the connections completed from the second position and for releasing the switches engaged in such calls.

20. In a telephone system, a cordless toll switchboard comprising two positions, toll lines, means at the first position for answering calls extended over said toll lines, automatic switches for extending connections

from calling toll lines to called toll lines or subscribers' lines, and means at each position for directly operating said switches.

21. In a telephone system, a cordless toll switchboard comprising two positions, toll lines, means at the first position for answering calls extended over said toll lines, automatic switches for extending connections from calling toll lines to called toll lines or subscribers' lines, means for directly controlling said switches from the first position, and means for transferring the directive control of said switches from the first position to the second position.
- 15 22. In a telephone system, a toll switchboard comprising two positions, toll lines incoming to the first position, toll selectors, service trunks extending from the first position to said toll selectors, link circuits individual to said service trunks for connecting the same with said toll lines, recording trunks incoming to the second position, other toll selectors, service trunks extending from the second position to said other toll selectors, link circuits individual to the second said service trunks for connecting the same with said recording trunks, toll line connectors accessible to all of said toll selectors, and means at each position for operating the associated toll selectors and any of said toll line connectors to extend connections to said toll lines.

23. In a telephone system, a line, a trunk, a link circuit connecting the line and the trunk, an operator's position circuit, means for splitting the link into two sections and for bridging the gap between the sections by said position circuit, a second operator's position circuit, means for splitting one section 40 of the link circuit into two sub-sections, and means for bridging the second gap by said second position circuit.

24. In a telephone system, a line, a trunk, a link circuit connecting the line and the trunk, an operator's circuit, means in the link for interposing the operator's circuit in the connection between the line and the trunk, a second operator's circuit, and means for interposing the second operator's circuit in 50 the connection between the first operator's circuit and the trunk.

25. In a telephone system, a plurality of lines, a like plurality of trunks, line circuits connecting the lines and trunks, an operator's circuit common to said links, means for splitting any link into two sections and for closing the gap between sections through said common circuit, a second operator's circuit, and means for splitting one section of the 60 split link into two sub-sections and for closing the gap between sub-sections through said second operator's circuit.

In witness whereof I hereunto subscribe my name this 14th day of January, A. D. 1930.

65 THOMAS F. CROCKER.
